UNITED STATES PATENT OFFICE

2,598,300

INTERNAL-COMBUSTION ENGINE

J Lewis Putt, Huntington Station, N. Y.

Application March 7, 1951, Serial No. 214,257

5 Claims. (Cl. 123—73)

1

This invention relates to internal combustion engines.

An object of this invention is to provide an engine of the character described having means to compress air in the crank case of the engine and to pass such compressed air to the carburetor of the engine.

Another object of this invention is to provide an engine of the character described having means to take air into the crank case on the up stroke of the piston and to compress air in the crank case on the down stroke of the piston and to simultaneously pass the compressed air from the crank case to the carburetor on said down stroke.

Yet another object of this invention is to provide in an engine of the character described, means to spray lubrication into the crank case in synchronization with the operation of the engine piston.

In accordance with the present invention air is taken into the crank case by means of an air inlet opening when the piston is on the up stroke. The air inlet opening is controlled by an air intake valve which operates in such a way as to allow the valve opening to open automatically or mechanically or electrically in synchronization with the engine. In accordance with the invention, a passage which leads to the air intake opening is covered by a suitable air filter. When the piston of the engine starts its downward stroke, the air within the crank case is compressed above atmospheric pressure and said air is then forced through the outlet valve, also operated automatically or mechanically or electrically in synchronization with the speed of the engine. The compressed air forced out of the air outlet valve of the crank case enters into the venturi of a carburetor or other vaporizing device for the engine.

With such apparatus I am able to obtain sufficient quantity of air required for complete combustion of the chamber of the cylinder. The utilization of the downstroke in the cylinder thus affords the opportunity of using the crank case in the manner above described as a compressor and at practically no added expense and without any other auxiliary power. This simple arrangement can be adapted easily to the crank case of any cylinder of nearly any kind of internal combustion engine.

The invention may be applied to a four cycle single piston internal combustion engine or to multi piston engines.

Another benefit obtained with my improved

2

apparatus is that the pressure created on the down stroke of the cylinder also captures loose vapors, fumes and oil that are present in the crank case and they are forced in the carburetor to bring about a more beneficial mixture which is eventually forced into the cylinder to result in better combustion, and to bring about a greater degree of economy of operation in the engine. At the same time better lubrication of parts of the engine will be accomplished.

Still a further object of this invention is to provide a simple, rugged and durable engine of the character described, which shall be relatively inexpensive to manufacture, sure and positive in operation, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of invention will be indicated in the following claims.

25 In the accompanying drawings in which is shown various illustrative embodiments of this invention;

Fig. 1 is a vertical cross-sectional view of an internal combustion engine embodying the invention;

Fig. 2 is an enlarged cross-sectional view taken on the line 2—2 of Fig. 1;

Fig. 3 is a view similar to Fig. 1 but illustrating a modified construction.

35 Referring now in detail to the drawings, 10 designates an internal combustion engine embodying the invention, here shown for the purpose of illustration, in the form of a single cylinder four cycle gasoline engine.

40 The engine 10 comprises an engine body or casing 11. Said body or casing 11 comprises a cylinder 12. Below the cylinder and extending therefrom is a crank case 13. The crank case 13 is formed with an air inlet valve opening 14 provided with a valve seat 15. Extending from the crank case 13 is a passage 16 communicating with the valve opening 14. Passage 16 leads to an air filter 17.

45 The valve opening 14 is preferably horizontally aligned with the crank shaft 19. Said crank case 13 is also formed with an outlet opening 20 in horizontal alignment with the inlet opening 14. Said crank case also is formed with a valve seat 21.

50 Communicating with the valve opening 20 and

valve seat 21 is a passage 22 which leads to the venturi or air inlet end of the engine carburetor 23. The outlet end of the carburetor 23 is connected by a conduit 24 which leads to the fuel inlet opening 25 of the engine.

A fuel inlet pipe 26 is connected to the carburetor 23 in the usual manner.

A butterfly valve 27 is located within the passage 24 to control the passage of fuel mixture to the valve intake 25. A usual fuel intake valve 28 controls the fuel inlet opening 25. The said valve opening 25 is located in the head of the engine. Also in the head of the engine is located the usual exhaust valve 30 which when open permits burnt gases to pass to the usual exhaust manifold 31. A spark plug 32 may be provided at the head of the cylinder.

Mounted for reciprocation in the cylinder 12 is a piston 35 connected by connecting rod 36 to an offset arm 37 of the crank shaft 19.

The valves 28 and 30 may be controlled by the usual mechanisms which control these valves in synchronization with the operation of the crank shaft 19. Such construction is well known in the art and is therefore not shown in the drawing.

Slidably mounted in pipe 16 and extending through air inlet opening 14 is a valve stem 40 on which is mounted a valve 41 adapted to seat on the valve seat 15 for closing the opening 14. The valve stem 40 projects into the crank case and at its inner end is a head 42.

Between the head 42 and the crank casing is a coil compression spring 43 which normally tends to seat the valve member 41 on the valve seat 15.

Slidably mounted in pipe 22 and extending through the valve opening 20 is a valve stem 50. The valve stem 50 carries a valve member 51 which will seat on the valve seat 21. The valve stem 50 projects into the valve casing 13, and at its inner end is a head 52. Interposed between the head 52 of the crank case is a coil compression spring 53 which normally tends to move the valve member 51 into engagement with the valve seat 21. On the crank shaft 19 is a cam 54. As the crank shaft rotates, the valve 54 will alternately move the valve stems 40 and 50.

It will now be understood that on the up stroke of the piston 35, the cam 54 will push back the valve stem 40 to unseat valve member 41 and open the valve opening 14 so that fresh air may enter the crank case.

On the down stroke of the piston 35, the spring 43 will move the valve member 41 onto the seat member 15, but the cam 54 will push back the valve stem 50 to unseat the valve member 51 to permit air to pass from the crank case through the passage 22 to the carburetor 23.

It will thus be seen that air is taken into the crank case on each up stroke and compressed air from the crank case is passed to the carburetor or other vaporizer on each down stroke.

Means is further provided to spray lubricating oil into the crank casing in synchronization with the movement of the piston 35.

Extending from or attached to the crank case 13 downwardly therefrom is a cylinder 65. Slidably mounted through a suitable opening in the crank case is a piston rod 66 having a head 66a at its upper end adapted to be engaged by the cam 54. At the lower end of the piston rod 66 and located within the cylinder 65 is a piston 67.

The cylinder 65 has a bottom wall 68 formed with an inlet opening 69 controlled by ball check valve 70 disposed within a cage 71. Connected to the inlet opening 69 by means of a conduit 72

is a lubricating oil tank or reservoir 73. Connecting the lower end of the cylinder 65 with the inside of the crank case is a conduit 75. Extending from the conduit 75 and located within the crank case is a spray nozzle 76.

Interposed between the crank case and the head 67 is a coil compression spring 77 surrounding rod 66, for lifting the piston 67.

It will now be understood that as piston 67 rises, the ball check valve 70 will open, and lubricating oil will be sucked into the cylinder 65. As the cam 54 presses down on the piston 67 to tension the compression spring 77, the ball check valve will close, and lubricating oil will be forced through the conduit 75 and through the spray nozzle 76 to spray the interior of the crank case to lubricate the parts. It will thus be seen that a single cam controls valves 41, 51 and pump piston 67.

In Fig. 3 there is shown an internal combustion engine 10a embodying the invention and illustrating a modified construction. The engine 10a is similar to the engine 10 except that the air intake valves and the air outlet valve of the crank casing are operated automatically. Thus engine 10a comprises a cylinder 12a from which extends a crank case 13a.

The crank case 13a is provided with an air inlet opening 14a controlled by an air inlet poppet valve 80. The air inlet opening 14a communicates through passage 16a to an air filter 17a. Said crank case 13a is also formed with an air outlet opening 20a controlled by a poppet valve 81.

The opening 20a connects with a passage 22a extending to the carburetor 23a which in turn is connected by passage 24a to the fuel intake opening 25a controlled by valve 28a, as hereinabove described.

The cylinder also is provided with exhaust manifold 31a controlled by exhaust 30a. Within the passage 24a is the usual butterfly valve 27a. Also fuel or gasoline is fed to the carburetor 23a through the conduit 26a.

It will now be understood that on the up stroke of the piston 35a the poppet valve 80 will automatically open to allow air to enter the crank case. During such action pressure is reduced in the crank case and the poppet valve 81 will close. On the downstroke of the piston 35a pressure in the crank case rises above atmospheric pressure to close the valve 80 automatically and at the same time to automatically open valve 81 to permit air from the crank case to pass through the passage 22a to the carburetor 23a or other vaporizer.

There is thus described an apparatus to obtain sufficient quantity of air required for complete combustion in the combustion chamber of any cylinder, at the same time insuring proper lubrication of the parts and utilization of the vapors, gasses or fumes from the crank case which are forced in the carburetor or other vaporizing device to bring about more beneficial mixture, which is eventually forced into the cylinder to provide for better combustion and hence greater economy of operation.

It will be understood that the device shown in Fig. 3 may also be provided with any suitable means for injecting a spray of lubrication into the crank case in synchronization with the operation of the engine. Furthermore, although the air intake and air outlet valves are shown to be operated mechanically as in Fig. 1 and automatically as in Fig. 3, they may also be operated electrically

or magnetically by use of suitable well known electrical or magnetic valves.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to protect by Letters Patent of the United States:

1. An internal combustion engine comprising a cylinder, a crank case extending from the cylinder, a piston within the cylinder, a crank shaft in the crank case, means to connect the crank shaft to the piston, means to take air into the crank case during the upstroke of the piston, a vaporizing device, means to pass air compressed from the crank case to the vaporizing device during the downstroke of the piston, and means to spray lubricating oil into the crank case in synchronization with the operation of the piston.

2. An internal combustion engine comprising an engine body provided with a cylinder and a crank case extending therefrom, an air inlet opening formed in the crank case, a passage connected to said air inlet opening, an air filter connected to said passage, a carburetor, means to connect the outlet end of the carburetor to the head of the engine, an outlet opening in the crank case, a passage interconnecting said outlet opening in the crank case with the inlet end of the carburetor, valves controlling the air inlet and air outlet openings of the crank case, and means controlled by the crank shaft to open the crank case air inlet valve on the upstroke of the piston, means to close the crank case air outlet valve during said upstroke of the piston, means on the crank shaft to open the crank case air outlet valve on the downstroke of the piston, and means to close the crank case air inlet valve during said down stroke of the piston.

3. An internal combustion engine comprising an engine body provided with a cylinder and a crank case extending therefrom, an air inlet opening formed in the crank case, a passage connected to said air inlet opening, an air filter connected to said passage, a carburetor, means to connect the outlet end of the carburetor to the head of the engine, an outlet opening in the crank case, a passage interconnecting said outlet opening in the crank case with the inlet end of the carburetor, valves controlling the air inlet and air outlet openings of the crank case, and means controlled by the crank shaft to open the crank case air inlet valve on the upstroke of the piston, means to close the crank case air

outlet valve during said upstroke of the piston, means on the crank shaft to open the crank case air outlet valve on the downstroke of the piston, and means to close the crank case air inlet valve during said down stroke of the piston, an oil pump, means connected to the oil pump for spraying oil to the inside of the crank case, and means controlled by the crank shaft to operate the oil pump.

4. An internal combustion engine comprising a cylinder, a crank case extending therefrom, a crank shaft and a crank case, a piston and a cylinder, means to connect the crank shaft with the piston, a cam mounted for rotation on the crank shaft, said crank case being provided with an air inlet opening, an air inlet valve controlling said opening, said crank case being further provided with an air outlet opening, a vaporizing device, means to connect the outlet opening to the inlet end of the vaporizing device, means to connect the outlet end of the vaporizing device to the head of the cylinder, an outlet valve controlling said outlet opening, said valves having enlarged heads at their inner ends within the crank case adapted to be alternately engaged by said cam.

5. An internal combustion engine comprising a cylinder, a crank case extending therefrom, a crank shaft and a crank case, a piston and a cylinder, means to connect the crank shaft with the piston, a cam mounted for rotation on the crank shaft, said crank case being provided with an air inlet opening, an air inlet valve controlling said opening, said crank case being further provided with an air outlet opening, a vaporizing device, means to connect the outlet opening to the inlet end of the vaporizing device, means to connect the outlet end of the vaporizing device to the head of the cylinder, an outlet valve controlling said outlet opening, said valves having enlarged heads at their inner ends within the crank case adapted to be alternately engaged by said cam, and means controlled by said cam to spray lubricating oil into said crank case.
